SAFETY DEVICE

Harold A. Mantz, Milwaukee, Wis., assignor to
 Milwaukee Gas Specialty Company, Milwaukee,
 Wis., a corporation of Wisconsin

Application May 20, 1940, Serial No. 336,090

3 Claims. (Cl. 158—117.1)

This invention relates to safety devices for gas or other fuel burners.

Burners of this sort are subject at times to what is known in the art as a flash-back. In the case of a gas burner, for example, the gas is usually mixed with air in a mixing chamber adjacent the burner, and the combustible mixture of gas and air is conducted to the burner where it is ignited by a pilot light. At times, the flame may flash back and the gas fuel burns in the chamber where the mixture of air and gas normally takes place. Where such a flash-back occurs, the gas often burns with insufficient oxygen, resulting in the production of a relatively large quantity of carbon monoxide, which is highly objectionable, and even dangerous, particularly in the absence of adequate flue connections.

One of the main objects of the present invention is to provide improved means in combination with a gas or other fuel burner, which means will operate automatically in the case of a flash-back to shut off the supply of fuel to the burner.

Another object of the invention is to provide improved means responsive to thermal conditions in the mixing chamber or at the outlet from which the fuel for the main burner is delivered for controlling the supply of fuel to the burner, and particularly for shutting off the supply of fuel to the burner in the event of an abnormal temperature at this location.

Another and more specific object of the invention is to provide in combination with a thermocouple placed in position to be heated by the pilot flame and connected to an electromagnet which is operative to maintain a valve in the fuel supply pipe leading to the burner open as long as the pilot flame is burning, a second thermocouple in position to be exposed to heat resulting from a flash-back and arranged wholly or partially to counteract or neutralize the action of the first thermocouple to release the valve for movement to closed position when a flash-back occurs.

Further objects and the features and advantages of the invention will be apparent from the following detailed description taken in connection with the accompanying drawing, in which:

Figure 1 is a diagrammatic view illustrating an embodiment of the present invention; and

Figure 2 illustrates diagrammatically another embodiment of the invention.

The invention can be embodied in a wide variety of forms for use with a wide variety of devices, but for purposes of illustration the inven-

tion has been shown more or less schematically as embodied in a manner automatically to close a valve in a fuel supply pipe leading to a burner in case of a flash-back, and also when the pilot light for the burner goes out.

Referring now to Figure 1 of the drawing, a gas or other fuel burner of any suitable or preferred type is conventionally illustrated at 10. The burner 10 may be the burner of a room or space heater, water heater, floor furnace, range, or any other burner. A gas or other fuel supply pipe 11 leads to the burner 10 for the delivery of gas or other fuel thereto—for example, through the outlet or delivery orifice 12 into the mixing chamber 13 in which the fuel is mixed with air which enters the mixing chamber through one or more ports 14. The combustible mixture of gas and air passes from the mixing chamber 13 through a conduit 15 to the burner 10 where it is delivered through the ports of the burner and ignited by a pilot burner 16 in juxtaposition to the main burner.

The safety shutoff valve 18 is incorporated in the fuel supply pipe 11. The particular form of the valve 18 may vary widely within the scope of the present invention. The particular valve shown more or less schematically in the drawing has an inlet 19 and an outlet 20 with a valve opening 21 for placing the inlet in communication with the outlet. A valve seat 22 is provided at one end of the valve opening 21 and, in the illustrated embodiment of the invention, a second valve seat 23 is provided at the opposite end of the valve opening. The pilot burner 16 is shown as supplied with fuel by a pilot supply pipe 25 shown as connected at 26 to the interior of the valve 18 between the valve seats 22 and 23, it being understood that this may be varied within the scope of the present invention.

The valve 18 is adapted to be closed by a valve member 28 to shut off the supply of fuel to the main burner and also, preferably, the supply of fuel to the pilot burner as shown in the drawing. The electromagnet 29 comprises a magnet frame 30 shown as of generally U-shaped form, although this may vary. The valve member 28 is connected by a stem 32 to an armature 33. When the armature 33 is placed in attracted position against the pole ends of the magnet frame 30 and the electromagnet is energized, as will presently appear, the electromagnet operates to hold the armature 33 in attracted position and the valve member 28 open for the supply of fuel to the main burner and also to the pilot burner 16. When the electromagnet 29 is deenergized, a

spring, indicated at 35, actuates the valve member 28 to closed position against the valve seat 22 to shut off the supply of fuel to the main burner and the pilot burner.

The electromagnet 29 has an energizing coil 36 which, in Figure 1, is shown as surrounding one of the legs of the magnet frame 30. This, of course, may vary where the magnet frame is of other form, or where only one coil is provided, as will hereinafter appear. The energizing coil 36 is connected in circuit with the thermocouple 38.

The thermocouple 38 is placed in position so that its thermojunction 39 will be heated by the pilot light when said pilot light is burning. The construction of the thermocouple may be similar to that disclosed in Oscar J. Leins Patent No. 2,126,564, granted August 9, 1938, or it may be of any other suitable or preferred form. One side of the energizing coil 36 is connected in circuit with one of the thermocouple elements—for example, the outer thermocouple element 40—through a lead conductor 41, and the other side of the coil 36 is connected in circuit with the other thermocouple element, namely the internal thermocouple element 42 of the particular thermocouple shown, through a lead conductor 43.

The outlet member 45, having the outlet or orifice 12 through which the fuel enters the mixing chamber 13 and which is shown of tubular form and as mounted on the adjacent end of the fuel supply pipe 11, constitutes one of the dissimilar metallic thermocouple elements of a second thermocouple 46. The other metallic thermocouple element 47 of the thermocouple 46 is shown of annular form surrounding and spaced from the element 45. The thermocouple elements 45 and 47 extend into the mixing chamber 13, and the inner end of the outer element 47 is contracted and joined to the element 45 to form a thermojunction 48. The thermojunction 48 is thus disposed so that it is responsive to thermal conditions in the mixing chamber 13, or at the outlet 12, and, more particularly, so that it will be heated by the flash-back flame 50 which burns at the outlet 12 in the case of a flash-back. Where there is no flash-back condition, of course the flame indicated in dotted lines at 50 is absent.

In the embodiment of the invention shown in Figure 1, the electromagnet 29 is shown as having a neutralizing coil 52 in addition to the energizing coil 36. The neutralizing coil 52 is shown as surrounding the other leg of the magnet frame 30 which, of course, may vary where the magnet frame is of other form, or where only one coil is employed. One side of the coil 52 is connected in circuit with the thermocouple element 45 through a lead conductor 54, and the other side of the coil 52 is connected in circuit with the other thermocouple element 47 through a lead conductor 55.

The heat of the pilot light on the thermocouple 38 energizes the electromagnet 29 sufficiently to hold the armature 33 in attracted position and the valve 28 open, assuming of course that there is no flash-back flame as indicated at 50, when the armature 33 is engaged with the pole ends of the magnet frame, but this thermoelectric current is not capable of moving the armature to attracted position and the valve member 28 to open position. Cocking means is therefore provided for actuating the armature 33 to attracted position and the valve member 28 to open position.

The cocking means comprises a cocking or reset

stem 60 coaxial with the valve member 28 and extending outwardly from the valve body. The outer end of the cocking stem 60 has a cocking or reset button 61 mounted thereon. The cocking stem 60 also has a flow interrupter disk 62 which, when the cocking stem 60 is pressed inwardly in the cocking operation, seats upon the valve seat 23 to shut off the supply of fuel to the main burner. A flow interrupter disk spring is provided at 63, and upon seating of the disk 62 upon the seat 23 in the cocking operation, the cocking stem is adapted to continue in its inward movement through the flow interrupter disk to bring the armature 33 fully to attracted position and the valve member 28 fully to open position. A spring 64 interposed, for example, between the valve housing and the cocking button 61 returns the cocking stem to its outwardly projected position upon completion of the cocking operation.

To start the operation of the system, the following sequence is followed:

The cocking stem 60 is pressed inwardly to actuate the valve member 28 to open position and the armature 33 to attracted position in contact with the pole faces of the magnet frame 30. This allows the fuel to flow through the pilot connection at 26 and pilot supply pipe 25 to the pilot burner 16 where the same is ignited. The stem 60 is held in depressed position until the pilot flame has heated the thermocouple sufficiently to energize the electromagnet 29 so that it will hold the armature 33 attracted thereto and, thereby, the valve member 28 in open position. The flow interrupter disk 62 seats upon the valve seat 23 to shut off the flow of fuel to the main burner as long as the cocking stem 60 is depressed.

When the electromagnet is energized sufficiently to hold the armature 33 in attracted position and the valve member 28 in open position, the cocking stem 60 is released, thus allowing the flow interrupter disk 62 to return to open or normal operating position. Fuel then flows out through the outlet 20 and fuel supply pipe 11 to the main burner where it is ignited by the pilot burner 16. If the pilot burner is not lighted to produce the thermoelectric current for holding the armature 33 in attracted position and the valve 28 open, the armature 33 will be actuated to retracted position and the valve member 28 to closed position upon release of the cocking stem 60. Also if, after being lighted, the pilot burner is extinguished, the armature 33 is released and the valve member 28 is actuated to closed position to shut off the supply of fuel to the main burner and to the pilot burner.

Upon normal operating conditions, the temperature of the thermojunction 48 is not high enough to set up the thermoelectric current necessary sufficiently to neutralize the current set up by the thermocouple 38, and the valve member 28 remains open as long as the pilot burner 16 is lighted. However, in the event of a flash-back with the pilot light burning, the flash-back flame, which then burns as indicated at 50, heats the thermojunction 48 and thereby sets up a thermoelectric current in the neutralizing coil 52. This current neutralizes the holding effect of the current in the energizing coil 36 sufficiently to release the armature 33 and the valve member 28 is actuated to closed position to shut off the supply of fuel to the main burner and the pilot burner. Upon discontinuance of the flash-back condition, the neutralizing action ceases to be effective, so that the system may be again set into operation.

by pressing the cocking stem 80 and lighting the pilot burner, as already described.

In the embodiment of the invention shown in Figure 2, the electromagnet 28', instead of having an energizing coil and a neutralizing coil, has only one coil 70 shown as wound around the legs of the magnet frame 30', it being understood that the coil 70 may be otherwise arranged, particularly where the magnet frame is of a form other than that shown.

In this case, one side of the coil 70 is connected in circuit with one of the thermocouple elements 40', 42' of the thermocouple 38' by a lead conductor 71. The other element of the thermocouple 38' is connected in circuit with one of the thermocouple elements 45', 47' of the thermocouple 46'. The other element of the thermocouple 46' is connected in circuit with the other side of the coil 70 by a lead conductor 72. With this latter embodiment of the invention, the thermocouple elements 45', 47' are so related as to set up a thermoelectric current in the electromagnetic circuit reverse to that set up by the thermocouple 38'. Consequently, upon the occurrence of a flash-back flame, as indicated at 50', the thermoelectric current which is set up reverse to that set up by the thermocouple 38' neutralizes the action of the thermocouple 38' sufficiently to release the armature 38' for movement to retracted position, whereupon the valve operates to closed position.

Certain embodiments of the invention have been illustrated in the accompanying drawing, but it is to be expressly understood that said drawing is for purposes of illustration only and is not to be construed as a definition of the limits or scope of the invention, reference being had to the appended claims for that purpose.

I claim:

1. In a flash-back safety device for gas burners, the combination with a gas burner, a gas and air mixing chamber, a conduit for conveying the gas and air mixture from said mixing chamber to the burner, a tubular jet member constituting one of the elements of a thermoelectric generator and extending through a wall of said mixing chamber with its inner end disposed within said mixing chamber and its outer end disposed outside said chamber, a fuel supply pipe connected to the outer end of said jet member for delivering gas into said mixing chamber through said jet member, a second thermocouple element extending through the wall of said mixing chamber and joined inside said chamber to said tubular jet member to form a thermojunction adapted to be heated by a flash-back flame, and thermoelectric conductors connected to said first and second mentioned thermocouple elements outside said mixing chamber.

2. In a flash-back safety device for gas burners, the combination with a gas burner, a gas and air mixing chamber, a conduit for conveying the gas and air mixture from said mixing chamber to the burner, a tubular jet member constituting one of the elements of a thermoelectric generator and extending through a wall of said mixing chamber with its inner end disposed within said mixing chamber and its outer end disposed outside said chamber, a fuel supply pipe connected to the outer end of said jet member for delivering gas into said mixing chamber through said jet member, a second thermocouple element of tubular form surrounding said jet member, said second thermocouple element extending through the wall of said mixing chamber and joined inside said

chamber to said tubular jet member to form a thermojunction adapted to be heated by a flash-back flame, and thermoelectric conductors connected to said first and second mentioned thermocouple elements outside said mixing chamber.

3. In a flash-back safety device for gas burners, the combination with a main gas burner, a pilot burner in juxtaposition to said main burner, a gas and air mixing chamber, a conduit for conveying the gas and air mixture from said mixing chamber to the main burner, a fuel supply pipe leading to said mixing chamber, a thermoelectric responsive valve in said fuel supply pipe and comprising a magnet frame and a pair of operating windings, a thermocouple in position to be heated by said pilot burner and connected in circuit with one of said windings, and a second thermocouple having a thermojunction disposed within said mixing chamber and connected in circuit with the other winding to neutralize the action of said first thermocouple when said second thermocouple is heated by a flash-back flame in said mixing chamber.

4. In a device of the class described, the combination of a burner, a mixing chamber for mixing gas and air and supplying the mixture to said burner, a gas supply pipe for supplying gas to said gas and air mixing chamber, a thermoelectric responsive control valve in said gas supply pipe comprising a magnet frame and a pair of operating windings, a pilot burner, a thermocouple in position to be heated by said pilot burner and connected in circuit with one of said windings to maintain said thermoelectric responsive control valve in open position as long as said thermocouple is heated by the pilot burner, and a second thermocouple connected in circuit with the other winding and having a hot junction disposed within said mixing chamber, said second thermocouple being normally deenergized and in position to be heated by a flash-back flame in the mixing chamber and adapted by energizing the winding connected therewith to neutralize the action of said first thermocouple for movement of said thermoelectric responsive valve to closed position.

5. In a flash-back safety device for gas burners, the combination with a main gas burner, a pilot burner in juxtaposition to said main burner, a gas and air mixing chamber, a conduit for conveying the gas and air mixture from said mixing chamber to the main burner, a fuel supply pipe leading to said mixing chamber, a thermoelectric responsive valve in said fuel supply pipe and comprising an electromagnet, a thermocouple in position to be heated by said pilot burner and connected in circuit with said electromagnet, and a second thermocouple having a thermojunction disposed within said mixing chamber and connected in circuit with said electromagnet to neutralize the action of said first thermocouple when said second thermocouple is heated by a flash-back flame in said mixing chamber.

6. In a fuel supply control system, a main burner, a fuel supply pipe connected to said burner, an automatic shutoff valve yieldingly urged closed for controlling flow of fuel to said burner, a pilot burner, means comprising an armature attached to said shutoff valve, and an electromagnet effective, when energized, for holding said shutoff valve open, said electromagnet comprising a magnet frame and a pair of windings each independent of the other, a thermoelectric generator adapted to be heated by the flame of the pilot burner for energizing one of said windings of said electromagnet to hold said

armature in attracted position and said shutoff valve open, and a second thermoelectric generator disposed to be subjected to the heat of a flame at the point of admission of fuel to said main burner, said second thermoelectric generator being connected in circuit with the other winding independently of the thermoelectric circuit including said first thermoelectric generator and acting, when heated by the latter flame, in opposition to said first thermoelectric generator.

7. In combination, a gas burner comprising a gas and air mixing chamber having a wall provided with air inlet openings, a tubular jet member constituting one of the elements of a thermoelectric generator and extending through the wall of said chamber with its inner end disposed within said chamber and its outer end disposed outside said chamber, a fuel supply pipe connected to the outer end of said jet member for delivering gas into said chamber through said jet member, a second tubular thermoelectric element surrounding said jet member and extending through the wall of said chamber with its inner end joined inside said chamber to said tubular jet member to form a thermojunction adapted to be heated by a flame in proximity to said jet member, an automatic shutoff valve yieldingly urged closed controlling flow of fuel to said jet member, an armature attached to said shutoff valve, and an electromagnet and energizing means therefor, said electromagnet being effective, when energized, for holding said armature in attracted po-

sition and said shutoff valve open, said electromagnet comprising a magnet frame and a winding on said magnet frame and connected in circuit with the tubular elements of the thermoelectric generator.

8. In combination, an electroresponsive device having an operating position and a safety position, said electroresponsive device comprising a magnet frame, a first operating winding on said frame, a flame responsive thermocouple connected in closed circuit relation with said winding and effective when heated by a flame to maintain said electroresponsive device in one of said positions, a second winding on said frame, and a normally deenergized thermocouple connected in closed circuit relation with said second winding independently of said first winding and to neutralize the action of said first thermocouple for enabling movement of said electroresponsive device to the other of its said positions when said second thermocouple is heated by a flame and thereby energized, the thermoelectric circuit including said first winding and said first thermocouple being normally free, when said first thermocouple is heated by a flame, of the resistance of said second winding and said second thermocouple, whereby for a given E. M. F. generated by the heat of a flame on said first thermocouple the holding action of the electromagnet is maximum.

30 HAROLD A. MANTZ.
